[57] CLAIM

The ornamental design for a wood splitting maul head, substantially as shown and described.

DESCRIPTION

FIG. 1 is a side elevational view of a wood splitting maul head showing my new design;

FIG. 2 is a front elevational view thereof;

FIG. 3 is a top plan view thereof;

FIG. 4 is a bottom view thereof;

FIG. 5 is a sectional view thereof taken along line 5—5 of FIG. 1; and

FIG. 6 is a diminished perspective view thereof.

The broken line disclosure of a portion of a handle is shown for illustrative purposes only.

Fig. 5.

Fig. 6.
